UNITED STATES PATENT OFFICE.

HARRY C. GAMMETER, OF CLEVELAND, OHIO, ASSIGNOR TO THE AMERICAN MULTIGRAPH COMPANY, OF CLEVELAND, OHIO, A CORPORATION OF OHIO.

LINOTYPE-SLUG.

1,122,727.

Specification of Letters Patent.

Patented Dec. 29, 1914.

Original application filed August 8, 1913, Serial No. 783,722. Divided and this application filed November 15, 1913. Serial No. 801,171.

To all whom it may concern:

Be it known that I, HARRY C. GAMMETER, a citizen of the United States, residing at Cleveland, in the county of Cuyahoga and State of Ohio, have invented a certain new and useful Improvement in Linotype Slugs, of which the following is a full, clear, and exact description, reference being had to the accompanying drawings.

10 The object of this invention is to provide a very cheap and efficient line slug adapted to be easily mounted in a grooved or slotted holder for printing. The holder may be a portion of a printing machine, or it may, for example, be an individual plate carrying a few of my slugs and constituting an address plate. An effective form of slug for use in such slotted or grooved holder is one wherein the slug has 20 lateral flanges adapted to rest on the top surface of the holder and receive the printing pressure. It has a shank extending into the slot or groove of the holder and has means to engage the under side of the 25 ledge to prevent the slug from coming out of place. The slug of the present invention has these characteristics; that is to say, it has a shank, a projecting head carrying the characters and has lugs projecting 30 from the sides of the shank some distance below the head and thus adapted to hold the slug in place. Such a slug as is described may be very conveniently made by casting the slug with up and down ribs on 35 its sides and thereafter removing the upper portion of the ribs adjacent to the head to leave the projecting lugs. The removal is effectively accomplished by mashing by pressure the upper portion of the rib. The 40 process of making such a slug as above described is claimed in my parent application No. 783,722, filed August 8, 1913, of which the present application is a division. This application relates to the slug itself.

45 In the drawings, Figure 1 is a perspective view of my improved slug; Fig. 2 is a cross section thereof on an enlarged scale; Fig. 3 is a side elevation of a portion of the slug on a scale similar to Fig. 2; Fig. 4 is a longitudinal section through the shank of the slug; Fig. 5 is a cross section of a holder or address plate carrying several of the slugs.

As shown in the drawings, A indicates

the shank of the slug, B the head thereof which projects in both directions, and C the lugs on the sides of the shank. If these lugs are made by first casting the slug with ribs and then meshing the upper portion of the ribs there may be left certain slightly projecting portions D of the mashed down ribs. The projection of these portions, however, is so small that they are negligible.

The slug is cast in a suitable machine with proper matrices opposite the head, so that characters E are formed on the head. After being cast, the upper portion of the ribs are mashed to leave the lugs C and any portion of the slug below these lugs is suitably removed, as described and claimed in my application referred to.

The slug described is not only very cheaply made but requires comparatively little metal; it is easily slid in place in a suitable holder, as, for example, the plate F shown in Fig. 5, and when in the holder remains in place. The printing pressure is taken by an original cast surface, namely; the under face of the head, wherefore the height-to-paper is accurate.

Having thus described my invention, what I claim is:

1. A printing slug comprising a shank, a projecting head, and spaced lugs on the side of the shank separated from the head.

2. A printing slug comprising a shank, a T-head, and lugs on opposite sides of the shank spaced from the head.

3. A printing slug comprising a shank, a head projecting in both directions therefrom, a row of lugs on each side of the shank, the top of said row being spaced from the bottom of the head.

4. A printing slug comprising a shank, an overhanging head, and spaced lugs on the side of the head, the tops of the lugs alining some distance below the head.

5. A printing slug comprising the combination of a shank, an overhanging head, lugs on the side of the shank spaced from the head and having their lower faces alining with the bottom of the shank.

6. A line slug having a shank, a T-head, and spaced lugs on the opposite sides of the shank, the lower faces of the lugs being flush with the bottom of the shank and the upper faces of the lugs spaced some distance below the lower faces of the head.

7. A line slug having a shank, a T-head, and lugs on the opposite sides of the shank separated by unobstructed spaces from the under sides of the T-head and projecting laterally less distance than the T-head.
8. As a new article of manufacture, an integral cast line slug having a shank, a T-head, and lugs on the sides of the shank separated some distance from the under

side of the T-head, the under side of such head preserving its original cast surface.

In testimony whereof, I hereunto affix my signature in the presence of two witnesses.

HARRY C. GAMMETER.
